TOY KITE

Frank Gene, also known as Yee Ming Hor,
Maricopa County, Ariz.

Application May 2, 1942, Serial No. 441,424

5 Claims. (Cl. 244—154)

This invention pertains to toy kites and has for its objects—

First, the provision of a kite of novel shape and design which is easily made with a minimum of parts;

A further object is to provide such a toy which can be easily and cheaply manufactured in quantity and in which the parts can be easily packed and shipped in compact or knocked down and prepared in such a manner that purchasers may easily assemble the devices and put them into operating condition with a minimum of tools and without the necessity of technical knowledge.

Further objects will appear hereinafter.

I attain the foregoing objects by means of the devices illustrated in the accompanying drawing in which—

Figure 1 is a top plan view of one form of kite embodying my improvements;

Figure 2 is a side elevation of the device as shown in Figure 1;

Figure 3 is a plan view of the wing only with the body portion removed to show the structure therebeneath;

Figure 4 is a fragmentary section view of the interrelation of the attaching parts taken substantially on line 4—4, Figure 1, but drawn on an enlarged scale;

Figure 5 is a plan view of a slightly modified form, and

Figure 6 is a plan view of a blank from which the body portion is formed.

The device consists essentially of a wing 2 and a vertical stiffening or body member 3, both of these portions are composed principally of paper. For this purpose a medium grade stiff paper may be used; cut and proportioned as hereinafter described. Each part is braced with light wooden beams, strips, or slats. Thus the wing member 2 is made preferably in the shape shown in Figure 3 with a straight leading edge 4 and a trailing edge 5 which is rounded toward the ends. A beam of light wood 6 is laid across this portion near the forward edge 4. The forward edge 7 is then folded to the rear over this beam as shown particularly in Figure 3, to form a triangular flap which performs two functions; first, to form a firm forward edge 4; and, second, to form a beam binding flaps 8 to hold the beam 6 in place. Folds on the right and left sides meet at an apex at 9. The underside of beam 6 is firmly cemented to the body of the paper composing the wing before it is placed in position.

In manufacture, this beam is cut to length and

coated on the side which is to be cemented with a type of cement which will dry but may be remoistened before use to secure adhesive properties, such as remoistening glue or the like.

In a similar manner the underside of wing fold of flaps 8 is coated with adhesive within the area bounded by the dotted fold lines 11. Likewise the area 10 in the central portion of this wing is coated with adhesive of the same material. Thus the whole wing may be prepared and manufactured simply by a cut out blank of paper, as shown in Figure 3, of the required properties as to stiffness, etc., marking it with fold lines to form the edge 4, and marked also to indicate the correct position of beam 6, and otherwise supplied at 10 with adhesive.

The vertical or body portion 3 is similarly prepared from a blank as shown in Figure 6. A stiffening beam 14 is attached by glue or adhesive to its center. The rear or lower portion is then rolled up on each side of its longitudinal center and the overlapping rear triangular portions 15 attached by adhesive. The same is true of the forward portion 20. These two overlapping portions are drawn somewhat angularly so as to bring the forward end 20 together to form a cone, and the rear portion together in the form of a somewhat enlarged, truncated cone-shaped body which may be termed a fuselage 15; the paper being shaped and slightly bent upon the lower angular fold lines so that the bottom of the body portion where it is cemented onto the wing is flat. This body portion is set upon the wing portion 2 so that the forward conical portion 21 extends forward over the leading edge of the wing by approximately one-fourth of its entire length while the rear portion extends to the rear of the wing as shown. The overall body length is approximately equal to the span of the wing portion. I have found that thirty inches for these dimensions affords a good flying kite. In the bottom of the fuselage portion 2 holes 22 and 23 are provided for the attachment of flying strings 24 and 25 forming a bridle to which the kite string is attached.

At the forward end of the fuselage a simulated propeller 30, cut from cardboard and twisted, may be attached by a pin 34 driven into the front end of the beam 14. A rubber band may be looped around this pin and stretched back on either side as indicated at 31, looped over notches in the ends of the cross beam 6 at 32 and then brought over the top of the forward portion of the fuselage at 33. When flown as a kite the wind will vibrate this rubber band, giving the semblance of the

noise of an airplane motor and the free turning simulated propeller will revolve, thus making the toy attractive.

At the rear of the fuselage and beyond the overlapping areas 15 the material of the blank is cut away so that it may be folded up at 34 and outward as at 35 on each side of a fold line 36 which is marked on the blank. This forms a contour simulating the rear elevators of an airplane.

When flying the extended portions 35 form flaps which yield to the force of the wind forming a varying V-shape, this tends to act as a stabilizer and eliminates the necessity of a tail.

In the modified form shown in Figure 5, the construction is similar in that the beam 46 acts the same as beam 6, the wing 42 the same as wing 2, except that it is shaped to simulate a bird's wing or the like. The longitudinal stiffening member 44 has the same effect as 14 in the first described figure and the flat vertical member 43 described figure and the flat vertical member 43 has the same structural relation as the fuselage or body portion 3, except that it is flat. These portions are joined by adhesive as shown by the broken away portion at 41. The vertical beam 44, however, does not extend the full length of the vertical member 43 but the rear portion of this member is replaced by a flat stiff piece of cardboard 47 which is of sufficient weight and stiffness to hold the rear portion of 43 flat as against the wind. This leaves a flexible unstiffened portion at 48. Due to the action of the wind the rear portion 49 of the vertical member 43 vibrates or flaps up and down, causing the kite to simulate diving maneuvers of an airplane. The underside of the wing and the vertical body portion may be painted or configured to represent a bird or airplane, as desired.

In use, either or both of the forms shown may be flown separately as an ordinary kite. The form shown in Figure 5 is attached by a single string inserted through the hole 50 in its central portion and wrapped around the vertical member 44. The vertical member 14, Figure 1, should be attached to the kite string by a bridle consisting of the strings 24 and 25 previously mentioned. Optionally both types may be flown together, with the modified form shown in Figure 5, let out first to fly above and over the form shown in Figure 1. Thus, this gives a simulation of a bird or menacing plane hovering over the lower kite which may be painted and configured to simulate a bombing or other type of plane. Due to the action of the wind on the rear portion 49 or tail of the form shown in Figure 5, it darts about in flight, while the other form flies steadily. This affords amusement and instruction.

I claim:

1. A toy kite comprising a transverse wing member and a longitudinal body member, said wing member being composed of a blank of a single sheet of paper, having a straight forward edge and a rear edge rounded forward at the ends, a transverse stiffening beam secured to the top side of said blank, the forward edge of said blank folded over rearwardly to form retention tabs for the ends of said beam and to form an inverted V shaped folded leading edge with the apex in the center thereof, said body member being composed of a longitudinal blank of paper shaped to afford a forward body portion and an extended tail rear portion strengthened longitudinally by a stiffening member attached to its top surface, said body member being attached to the top surface of said wing member.

so that its center is at right angles to the supporting member on said wing, and so that the under surface of said body affords support of substantial width for the rear edge of said paper portion of said member.

5. A toy kite comprising, in combination, a wing member fabricated from a sheet of paper having a straight forward edge, a rear edge curved forward at the ends, a lateral stiffening beam cemented to its upper surface placed parallel to said forward edge, and a leading edge formed by that part of the sheet, forward of the stiffening beam, being folded along lines extending from the mid point of the leading edge to the ends of said beam, to form a stiffened leading edge, a longitudinal body member formed from a paper blank, with the edge portions folded upward at the ends and overlapping to form forward and rearward conical portions simulating a fuselage, a longitudinal stiffening beam cemented to the center of said blank bent upward and outward on each side to form a stabilizing member, said body member being cemented to the center of said wing member in right angular relation thereto.

10. A toy kite comprising, in combination, a wing member fabricated from a sheet of paper having a straight forward edge, a rear edge curved forward at the ends, a lateral stiffening beam cemented to its upper surface placed parallel to said forward edge, and a leading edge formed by folding triangular tabs rearwardly from each side of the center thereof, a longitudinal body member formed from a paper blank, with the edge portions folded upward at the ends and overlapping to form forward and rearward conical portions simulating a fuselage, a longitudinal stiffening beam cemented to the center of said blank, and a rear portion of said blank bent upward and outward on each side to form a stabilizing member, said body member being cemented to the center of said wing member in right angular relation thereto, to afford support for the central portion 30 of the rear edge of said wing material, a rubber band stretched over the body portion, secured to the ends of said wing portion and the forward end of said fuselage, and a free turning propeller attached to the forward end of said body portion.

15. A toy kite comprising a transverse wing member composed of a blank of paper, shaped to the outline of an airplane wing, a transverse stiffening beam cemented to the upper side thereof to the rear of the front edge of said blank, a leading edge formed by folding back and cementing the ends of the forward edge along lines extending from the center to the ends of said stiffening member, the trailing edge thereof being free to flex, in combination with a longitudinally extending centrally positioned body member consisting of a paper blank with its lateral edges rolled up and lapped over forming a cylindrically shaped body with the ends slightly tapering, with an end portion of said blank folded outwardly to form stabilizing tail surfaces, said body member being cemented to the central portion of said wing member so that said transverse and longitudinal stiffening members cross and so as to afford support for the central portion of the rear edge of said wing member.

20. A kite comprising a transverse wing member made from a single paper blank having a straight forward edge and a rear edge curved from the center toward the forward edge on each

side, a single transverse stiffening beam attached to the top of said blank to the rear of said forward edge of said blank, this blank, being folded up and over along lines extending from its center to the forward edge of said stiffening member, said folds forming the leading edge of the wing member, and triangular shaped tabs, so formed, being attached to the material of the blank to afford additional retention for said stiffening beam; together and in combination with a single longitudinally extending body member formed from a paper blank, a longitudinal stiffening beam thereon, being cemented along the central portion thereof, said blank being rolled

up from the edges and lapped over and the lapped portions cemented to simulate a fuselage, and with the rear portion of said edges folded outward forming laterally extending tabs adapted to act as stabilizing surfaces; said body member being cemented to the top of said wing member so that the rear edge of the wing material is supported by the under side of said body member within its central portion, while the rear edges of the material on each side thereof are free to flex.

FRANK GENE,
